LUTHER H. BUCHANAN, OF PASADENA, ASSIGNOR OF ONE-HALF TO J. DE BARTII SHORB, OF SAN GABRIEL, CALIFORNIA.

ELECTRIC-ARC LAMP.

SPECIFICATION forming part of Letters Patent No. 447,746, dated March 3, 1891.

Application filed July 8, 1890. Serial No. 358,039. (No model.)

To all whom it may concern:

Be it known that I, LUTHER H. BUCHANAN, a citizen of the United States, residing at Pasadena, in the county of Los Angeles and 5 State of California, have invented certain new and useful Improvements in Electric-Arc Lamps, of which the following is a specification.

My invention relates to arc lamps, and my 10 improvements include the shape of the carbons, the means for feeding them, and the cut-out.

My object is to produce an arc lamp that 15 will burn a great length of time while still employing but one set of carbons, and which lamp, when burning, will throw no objectionable shadow. These objects I attain by means of the construction and combination of parts in which my invention consists, as hereinaf- 20 ter described and claimed.

In the accompanying drawings, Figure 1 is 25 a side elevation, partly in section, of my complete lamp. Fig. 2 is a longitudinal section on line 2-2 of Fig. 1, a portion of the feed- 30 wheel being broken out. Fig. 3 is a detail 25 plan of the carbons; and Fig. 4 is a detail view of the coils, taken from the side opposite that of Fig. 1 and showing the cut-out 35 connections.

In the upper part of a suitable frame X are 30 secured the main and shunt coils A and B, respectively, and to a stud c is pivoted the armature C, having sides or wings adapted to overlap the cores of the coils alternately, 35 according as it may be more or less attracted by either of said coils. On each side of the pivot-stud c is a set-screw c' to limit the swing of the armature. A downwardly-projecting extension c² of the armature engages the edge 40 of the feed-wheel D when moved in the direction of the arrow, Fig. 1, by the attraction of coil A, and is retracted by a suitable spring c³. This feed-wheel is secured to the upper end of the short vertical shaft G, and is pro- 45 vided with an elastic periphery d, preferably consisting of a round rubber band fitted to a peripheral groove of the wheel. This is to insure a better engagement of the armature-extension with the wheel to rotate it. The 50 lower end of shaft G has a bevel-pinion g, which engages a bevel-pinion H, of insulating

material, which in turn engages with a bevel- 55 pinion g' on the upper end of a short vertical shaft G'. A bracket J, secured to the under side of the frame, has four horizontal arms 1, 2, 3, and 4 of insulating material. The upper shaft G has its bearings in the frame X and arm 1. The pinion H has its horizontal bearings in the arm 2, and the lower shaft G' has its bearings in arms 3 and 60 4. It will thus be seen that the two shafts are thoroughly insulated from each other.

Above the frame X the shaft G has a sleeve F loosely mounted upon but capable of being secured to it by means of set-screw f, and 65 to this sleeve is secured the inner end of a coil-spring E, the other end of which is secured to the frame X at e. The tension of the spring is adjusted by turning the sleeve F on the shaft and securing it by its set- 70 screw, and the spring is so arranged as to have a tendency to turn the wheel D in a direction contrary to that in which it is turned by the armature-extension, and to feed the carbons toward each other, as hereinafter ex- 75 plained.

To the shaft G is secured an arm K, extending out and down and carrying at its end a clip k, provided with set-screw k' for clamping one of the carbons L in said clip, 80 said clip and carbon being below the plane of the lower end of the bracket J. To the shaft G' is secured an arm K', extending out to the same distance from the center of the shaft as the arm K, and carrying at its outer end a 85 clip k², having set-screw k³ for clamping the other carbon L' and carrying it in the same plane with that of the carbon L, carried by arm K. These two carbons, as shown in Fig. 3, when new and placed in the clips form a 90 nearly complete disk or circle, and each forms a sector, one greater and the other less than half the circle. In trimming the lamp the arms K K' will be turned back against the action of spring E until nearly or quite in 95 contact with the two sides of bracket J. The carbons will now be secured in the clips, and the spring will cause their radial edges l l' to abut against each other.

The positive wire P from the dynamo or 100 other source of electrical energy after passing through the large coil A is connected to

the arm carrying the larger sector-carbon in any ordinary or preferred manner, and the other wire N is similarly connected to the arm carrying the smaller sector-carbon, or the 5 said wires may have spring-contacts pressing directly against the surface of the sectors.

In operation, when the current is turned on, the energizing of coil A will attract the armature toward it and cause the extension c² 10 to engage the wheel D and rotate the shafts against spring E to separate the edges l l', thus striking the arc, which will be formed at some point between said edges, usually at the center l², and from said starting-point 15 will move back and forth between the edges l l', the arc remaining at the point where the two edges approach each other most closely, and when this point is somewhat consumed moving to the next points which are nearest 20 together. When the edges have been consumed to such an extent that there no longer remains a point where the arc of the proper length can form, the increase of current in shunt-coil B and decrease in main coil A 25 cause the armature C to move toward coil B and its extension c² to leave the wheel D. The spring E now feeds the carbons in the manner above described until the arc is of the proper length, and the current in coil A 30 causes the extension of the armature to again engage the wheel and prevent further feed.

Referring now particularly to Fig. 4, my improved cut-out is to be described as follows: A metallic strip A' is secured, as by screws a, 35 to the insulated heads of the coils, and is provided with curved ends a' b', the former being adjacent to but not in contact with the upper side of the projecting end of the iron core of coil A, and the latter being similarly 40 arranged with respect to but underneath the end of the core of coil B. A curved strip a² of soft iron is pivoted to the head of coil A and extends under its core, and a similar strip b² is similarly pivoted with relation to 45 the core of coil B. At their pivotal points these two curved strips have connections a³ and b³, respectively, with the wire of the main circuit—one each side of the carbons—and the strip a² has a curved spring or thin 50 strip of metal a⁴ secured to it and carried over the core and between it and the end a' of strip A', and adapted to make contact with said end a' when the pivoted strip a² is attracted by the magnet A.

55 The cut-out operates as follows: When the current enters the lamp and its coils A and B, the two curved strips are attracted to the respective cores, and the thin spring or strip a⁴ makes contact with the end a' of strip or bar A', and as long as there is any current through the lamp remains in this position. At the same time the curved strip b² is lifted from the end b' of bar A, and thus prevents short-circuiting through said bar; but if coil 60 B should be broken or burned out attraction for strip b² would cease and it would fall in contact with the end of bar A', and thus cut

the lamp out, the current flowing through the coil A, connection a³, strip a², spring a⁴, strip or bar A', strip b², and connection b³ back to 70 the dynamo.

From the foregoing, taken in connection with the accompanying drawings, it will be seen that the construction and arrangement of my lamp are such that the vertical dimensions are much less than can be had in the ordinary arc lamp in which vertical carbons are employed, and that, consequently, the lamp can be placed in rooms or show-windows having low ceilings. The carbons having their 80 contiguous edges l l' elongated and in substantially the same horizontal plane there are no parts of the lamp below the arc and no objectionable shadows are cast, and the large amount of carbon that can be contained in 85 the disks or sectors is such that the lamp can be used a very long time without trimming.

It is obvious that I may secure one of the carbon sectors against motion and feed the other sector only without departing from the 90 principle of my invention.

Having thus described my invention, I claim—

1. In an arc lamp, the combination, with two sector-shaped carbons, of pivoted supporting and carrying arms therefor, one of said arms being pivoted to a support, the center of the pivot and the inner ends of the radii of both sectors being in alignment.

2. In an arc lamp, the combination, with two sector-shaped carbons, of pivoted supporting and carrying arms therefor, the center of the circle of which the carbons are sectors being in line with the center of motion of the arms, and gearing between the said arms, substantially as described.

3. In an arc lamp, the combination, with two sector-shaped carbons, of pivoted carrying-arms therefor, the center of the circle described by the carbons being in line with the center of motion of the arms, gearing between the said arms, a wheel carried by the shaft of one arm, a magnet and armature for moving said wheel in one direction, and a spring for moving the shaft and wheel in the other direction, substantially as described.

4. In an arc lamp, the combination, with a pair of carbons, one of which is connected to an arm carried by a rotary shaft, of a wheel on said shaft, a magnet having a portion of its armature engaging the periphery of said wheel, and a spring for rotating said shaft, substantially as described.

5. In an arc lamp, the combination, with a pair of carbons, one of which is connected to an arm carried by a rotary shaft, of a wheel secured to said shaft and having an elastic periphery, and a magnet having its armature engaging said periphery, substantially as described.

6. In an arc lamp, the combination, with a pair of carbons, one of which is connected to an arm carried by a rotary shaft, of a wheel secured to said shaft and having an elastic

periphery, a magnet having its armature engaging said periphery, a sleeve adjustably secured to the said shaft, and a spring having one end secured to the sleeve and the other end to the frame, substantially as described.

7. In an arc lamp, the combination, with a pair of carbons, one of which is connected to an arm carried by a rotary shaft, of a wheel secured to said shaft, main and shunt magnets in the circuit of the lamp, a pivoted armature having a wing for each magnet and an extension engaging the periphery of the wheel, and an adjusting-screw each side of the pivot of the armature, as described.

8. In an arc lamp, the combination, with the frame, of the bracket J, having insulating arms 1, 2, 3, and 4, a shaft journaled in the lower arms 3 and 4 and having an arm carrying a carbon, a shaft journaled in the upper arm 1 and the frame and having an arm carrying the other carbon, a bevel-pinion on each shaft, and an intermediate pinion of insulating material meshing with said shaft-pinions and journaled in the arm 2 of the bracket, as set forth.

9. A cut-out for arc lamps, consisting of main and shunt coils in the circuit, a metallic bar extending from one coil to the other, but insulated therefrom, an armature of the main coil connected to the main circuit and having an extension adapted to make contact with one end of the said bar, and an armature of the shunt-coil connected also to the main circuit and adapted to make contact with the other end of said bar when released by the core of said shunt-coil, substantially as described.

10. The combination, with the coils A and B, of the bar or strip A', the pivoted strips a² and b², the former having an extension a⁴, and connections from the two pivoted strips to the main circuit, substantially as described.

In witness whereof I have hereunto signed my name in the presence of two subscribing witnesses.

LUTHER H. BUCHANAN.
